UNITED STATES PATENT OFFICE.

JOSEPH A. GOLDSTEIN, OF BROOKLYN, NEW YORK.

CABLE-GRIPPING DEVICE.

SPECIFICATION forming part of Letters Patent No. 350,585, dated October 12, 1886.

Application filed April 15, 1886. Serial No. 198,908. (No model.)

To all whom it may concern:

Be it known that I, JOSEPH A. GOLDSTEIN, a citizen of the United States, residing at Brooklyn, in the county of Kings and State of New York, have invented a new and useful Improvement in Cable-Gripping Devices, of which the following is a specification.

My invention relates to cable-road grippers, and has for its object the provision of devices attached to a car, truck, or carriage whereby movable cables shall be gradually gripped and released.

My invention further relates to devices connected to and combining brake-levers with the mechanism that operates the grippers, so that said brake-levers are brought into action by the same motive power that governs the grippers.

My invention comprises certain novel forms of grippers, their carriers, and combinations thereof with the brake-levers, as illustrated in the drawings, hereinafter fully described, and specifically set forth in the claims.

Referring to the accompanying drawings, in which like letters of reference point out similar parts on each figure, Figure 1 is a side elevation of my improved gripping and brake attachment with a portion of a railroad-car partly in section. Fig. 2 is a modification of the same without the brake, and illustrating the operation of my invention as a horizontal grip. Fig. 3 is a longitudinal section on the line xx , Fig. 2. Fig. 4 is an end elevation of Fig. 2. Fig. 5 is a vertical section on line yy of Fig. 1. Fig. 6 is a cross-section on the line zz of Fig. 1. Fig. 7 is a diagrammatic detail showing operation of car-brake.

In the drawings, A is the car-bottom; B, wheels; C, axles; D, track-rail; E, cable; F, bracket to which the gripping attachments are secured; G, screw to operate gripping and brake mechanism; H, cross-beam, carrying brake-levers at its ends; I, brake-shoes; J, brake-levers; K, pivoted links to support outer ends of brake-levers; L, central screw-threaded portion of cross-beam H; M, sliding gripper-carrier; N, upper gripper-rollers; O, levers pivoted to carrier M and bracket F, and operating the movable gripping-sheaves P; Q, fixed gripping-sheaves attached to bracket F, (Fig. 1,) or car-bottom, (Fig. 2;) R, brake-chain; S, sprocket-wheels; T, brake-spindle

or shaft; U, hand brake-wheel; V, drum for chain R; W, links, (Fig. 2,) connecting movable sheaves P with levers O; W', plates attached to car-frame, provided with pivot-stud 6; X, ways in which carrier M slides; Y, screw-threaded boss on upper end of slide M. 1 is curved end of beam H; 1^a, recess for reception of inner ends of brake-levers J; 2 to 11 inclusive, pivotal points of lever, links, &c.

From the above description of the several parts of my device, in connection with the drawings, to which reference is made, the construction of my improved gripper and its operation will be readily understood by all familiar with the art to which my invention is allied.

One of the principle objects of my invention is to provide means whereby a movable cable shall be gripped when said cable is deflected from a right line. This result is attained by my improvement, whether the cable is gripped horizontally or vertically, by reason of the arrangement of a group of rollers, N, each independently journaled at the curvilinear end of the sliding carrier M.

I will first describe my invention as adapted for employment where a movable cable, E, travels in a trough or hollow space below the roadway, in which case such cable will be gripped vertically, and where, by its own weight or from other causes, the cable is liable to deflect downwardly from a right line between each of its supporting sheaves or rollers. (The latter being not shown in the drawings.)

Attached to the bottom of a car, A, and securely bolted thereto, is a depending bracket, F. Upon its outer face, and near the lower corners thereof, pivoted at 10, are gripping-sheaves Q, on which the cable E rests when brought to bear upon the peripheries of said sheaves, which are grooved to receive the cable. Said sheaves Q when actuated on form the lower grips, as will presently appear. The bracket F is provided with a central vertical opening extending from its upper portion a given length, to provide a passage for the several movable parts of the device, as plainly shown in Fig. 1. At the lower end of said passage is an open box or way, X, through which the upper limb or arm of the carrier M is free to slide, which way guides said carrier and keeps

it from lateral displacement. The carrier M below the arm which slides within the way X, is widened, and such widened portion at its lower end is shaped to describe the segment 5 of a circle. This portion I herein denominate as a "sector-head." Upon this sector-head, journaled at 9, are a series of upper grip-sheaves, N, having grooved peripheries. Upon either side of the sector-head, and above the 10 sheaves N, are pivots 8, which take into elongated slots of levers O, said levers at their opposite ends being pivoted at 6 to the bracket F. Attached to each of the levers O, and pivoted thereto at 7, is an upper gripping-sheave, P, which sheaves P, when the device is operated to grip the cable, are normally in a line above the lower grip-sheaves, Q, and said gripping-sheaves P and Q, as is obvious, will intermediately embrace and clasp the 15 cable E when brought to bear against it, the pivot 8 having requisite play within the elongated slot of the levers O. The carrier M is propelled within the ways X by action of a screw, G, which passes through a screw-threaded aperture of the boss Y. Said screw G also passes within and through a screw-threaded opening of the cross-beam H, and carries said beam up and down, thereby operating the 20 brake-levers, as will be more particularly described hereinafter. The upper end of the screw G passes through an orificed plate forming a part of the bracket F, as plainly shown in Fig. 1. Below said plate, and surrounding the screw G, is a sprocket-wheel, S, around 25 which is wound the operative chain R, which extends therefrom, and is connected to a sprocket brake-wheel, S', attached to the brake-spindle T. It will be readily understood that by turning the hand-wheel U the 30 carrier M will be caused to slide within the ways X, and that the brake-beam H will be carried thereby at the same time. Extending from the beam H, and pivoted thereto at 2, are brake-levers J J, to the free ends of which, 35 pivoted at 3, are brake-shoes I I. Said levers J are upheld by hanging links K pivoted to the car-truck at 5, and at their opposite ends pivoted at 4 to the levers J. It is obvious 40 that the same action that will cause the carrier M to be brought to and withdrawn from the cable E will bring the shoes I against and away from the truck-wheels B. Thus by one and the same operation the cable E is gripped and the brakes withdrawn from the traction- 45 wheels B, and thereby gentle and gradual motion will be imparted to the traveling carriage, without jar or jolt. In like manner when it is desired to stop the progress of the carriage the withdrawal of the grippers from the cable 50 and the application of the brakes to the truck-wheels being concurrent, a whole train is gradually and easily brought to rest without any sudden impact.

I have thus far confined my description to 55 the arrangement of my invention in connection with its brake-operating mechanism to the device shown in Fig. 1, and adapted and

intended for application to a movable cable traveling in a conduit below the level of the road-bed; but it is equally adaptable and practicable for use where such cables are elevated above the roadway and to the operation of the device independent of its brake attachments. I will also observe that while in describing the device illustrated in Fig. 1, for the purpose 75 set forth, I have, for fully explaining my invention, included the brake-operating mechanism and attachments.

I do not desire to be understood as limiting my invention to the combination of the brakes 80 and their attachments, as my gripping device can be applied in any direction without the brake-co-operating elements, the sheaves P, Q, and sector-head gripping-sheaves N constituting of themselves perfect cable-grippers. 85

It is fully within the scope of my invention to employ gripping-sheaves arranged and operated, as hereinbefore described, to grip a cable laterally. This form of its utilization is illustrated in Fig. 2, wherein my improved 90 carrier is shown as secured to the under part of the floor of the carriage. Instead of being attached to said floor, the device may be arranged within an independent frame-work hanging from and in alignment with the plane 95 of the floorway, as is common in analogous devices. In this form the bracket F is not necessary. The carrier M is provided with a sector-head onto which is journaled a series of grip-sheaves, N, as before described, the operative 100 screw G passing through a drum, V, around which is wound an endless chain, R, reaching to and wound around the sprocket-wheel of the brake-spindle. Where the bracket F is dispensed with, the levers O are pivoted at 8 to 105 extensions of the boss Y, and at their opposite end, within an elongated slot, passes a stud or pivot, 6, extending from a plate, W', these levers O having pivoted thereto at 11 short links W, pivoted to which at 7 are grip-sheaves P, the opposite sheaves, Q, being pivoted at 10 to the frame or floor of the carriage. 110

In practicing my invention, suppose the carriage is at rest, and it is desired to start the train. The first thing to be done is to release 115 the truck-wheels from brake-pressure, and then to gradually grasp the moving cable. This is effected by bringing the carrier M against said cable, and it will be seen that the central sheave N thereof will be the first to exercise the gripping function, those to the right and left thereof being in succession brought into action, and in due time the respective gripping-sheaves P Q will grasp the cable, all of which will be done without imparting any 120 sudden jolt to the carriage or train, which is not the case when the opposite gripping-sheaves are respectively in right lines, and where, as is obvious, the grip-pressure from all the sheaves is exactly the same and brought 125 into action simultaneously. In the drawings I show a single sheave, Q, pivoted at each corner of the bracket F, Fig. 1, and in like manner two single sheaves, Q, pivoted at 130 10

in position on the floor of the car, (see Fig. 2;) but it is entirely within the scope of my invention to increase the number of sheaves. It is obvious, also, that one or more sheaves, 5 P, may be pivotally connected to the levers O, and be within the scope and purview of my invention.

While the superior advantage of my gripping mechanism will be obvious to all familiar with analogous devices, my invention has another functional power which is of great importance. The cable E can in no instance be taut, and it is liable to sag and deflect at various points of its length and under various 15 conditions, thus causing the grippers in common use to lose their hold, and, as is frequently the case, throw the car from the track; but this defect is entirely overcome by reason of the arrangement of the sheaves N upon the 20 sector-head of the carrier M, which is intermediate of the true grippers P Q, said sector-head sheaves taking up all the slack of the cable first at the start, and then continuously as progression is made.

Having now fully described my invention and its operation, what I claim, and desire to secure by Letters Patent of the United States of America, is—

1. In a cable-gripping device, the rollers N, 30 journaled in a curvilinear line upon the sector-head of a propellible carrier, M, substantially as described.

2. In a cable-gripping device, a bracket, F, attached to a truck-bottom, provided with 35 open ways X X, within which a carrier, M, is free to slide, in combination with a carrier having a sector-head upon which are journaled in a curvilinear line a series of sheaves, N, as and for the purpose intended, substantially as 40 set forth and described.

3. In a cable-gripping device, a propellible carrier having upon either side at or near the lower end thereof, pivoted levers O, upon which are journaled one or more grip-rollers, P, in combination with opposite pivoted grip- 45 rollers, Q, substantially as described.

4. In a cable-gripping device, a propellible grip-carrier provided with pivoted gripping-sheaves, in combination with brake-levers J J, pivoted to a common cross-beam, said brake-levers adapted to be brought into action by the same mechanism that operates said carrier, as and for the purpose intended, substantially as described. 50

5. In a cable-gripping device, a propellible carrier, M, upon which are journaled a series of grip-sheaves, N, said carrier-head having upon its either side levers O, pivotally connected at their respective ends to said carrier 60 and to fixed carriage attachments, said levers having pivoted thereto grip-sheaves P, adapted to be swung into position to grip the cable, in combination with opposite pivoted grip-sheaves, Q, as and for the purpose intended, 65 substantially as described.

6. In a cable-gripping apparatus, the brake-lever bar H, carrying at its either end a pivotally-connected brake-shoe lever, said bar having a central screw-threaded bore, in combination with a common screw, G, passing through said bore and the bore of the boss Y of a propellible carrier, M, whereby both the brake-lever bar and carrier are simultaneously lifted forward and backward, as and for the 75 purpose intended, substantially as described.

JOSEPH A. GOLDSTEIN.
